(57) **CLAIM**

The ornamental design for a housing for a carbon arc gouging torch, as shown and described.

DESCRIPTION

FIG. 1 is a front perspective view of the design for a housing for a carbon arc gouging torch;

FIG. 2 is a further front perspective view thereof;

FIG. 3 is a rear perspective view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

In these drawings, the solid lines illustrate the claimed ornamental design, whereas the broken lines illustrate portions of the housing for a carbon arc gouging torch that form no part of the claimed ornamental design.

1 Claim, 8 Drawing Sheets(56)
